CLAIM

We claim, the ornamental design for head phone, as shown and described.

DESCRIPTION

FIG. 1 is a perspective view, showing our new design,
FIG. 2 is a rear view thereof,
FIG. 3 is a front view thereof,
FIG. 4 is a left side view thereof,
FIG. 5 is a right side view thereof,
FIG. 6 is a bottom view thereof; and,
FIG. 7 is a top view thereof.
